BLOWPIPE TOY

Joseph B. Barricks, Des Moines, Iowa

Application June 21, 1954, Serial No. 31,092

Term of patent 14 years

(Cl. D34—15)

FIG. 1

FIG. 2

To all whom it may concern:

Be it known that I, Joseph B. Barricks, a citizen of the United States and resident of Des Moines, in the county of Polk and State of Iowa, have invented a new, original, and ornamental Design for a Blowpipe Toy, of which the following is a specification, reference being had to the accompanying drawing, forming part hereof, in which:

Fig. 1 is a top plan view of a blowpipe toy showing my new design;

Fig. 2 is a side elevational view;

Fig. 3 is a rear view; and
Fig. 4 is a front view.

I claim:

The ornamental design for a blowpipe toy, substantially as shown.
